Specification for Design.

Patented Nov. 18, 1919.

Application filed May 7, 1919. Serial No. 295,479. Term of patent 14 years.

To all whom it may concern:

Be it known that I, MARIO PERUZZI, a citizen of the United States, residing at Wilkes-Barre, in the county of Luzerne and State of Pennsylvania, have invented a new, original, and ornamental Design for a Box, as shown in the accompanying drawing and described in the following specification.

The invention relates to an improved design for boxes and particularly to metal boxes and is illustrated in the accompanying drawings wherein:

Figure 1 is a perspective of the box with the cover applied.

Fig. 2 is a plan view with the cover removed.

Fig. 3 is a cross section through a portion of the box rim to show its shape.

The box comprises side walls 2 which are about twice as long as they are high and form a square in plan with conspicuously rounded corners 3. The upper end of the box has a rim 4 forming a perpendicular seam-ridge 5 at the edge of the top. The rim is trough-like in section as seen at 6, and has a rectangular seat flange 7 to take the cover 8. This latter is dished as at 9.

I claim:

The ornamental design for a box as shown and described.

MARIO PERUZZI.
